NECKTIE

John T. Scully, New York, N. Y.

Application February 12, 1930, Serial No. 427,731

8 Claims. (Cl. 2—153)

This invention relates to improvements in neckties and has especial reference to that class of necktie which is worn by males with a collar either attached to, or separate from, a shirt 5 neckband.

An object of the invention is to provide a necktie, in either the conventional four-in-hand or bow knot form, in which the knot is permanently formed and which includes a device to engage a collar button whereby the necktie is held in position to the collar.

A further object of the invention is the provision of a form element which carries means to engage a collar button and which, in addition, is adapted to carry a necktie in untied form and on which the necktie may be tied by the user.

A still further object of the invention is the provision of a combination of necktie holding means wherein means are provided with the necktie to cooperate with means provided in a collar button for the purpose of securing the necktie in proper position to a collar.

Other objects will hereinafter appear.

In neckties of the class in which the tie-knot is already formed for the wearer, a well known variety is the kind that provides a band to extend around the collar band and which may be fastened and unfastened to itself or the tie knot. Another well known variety is the kind wherein 35 the tie carries a slotted or "keyed" member to straddle the shank of the collar button.

In the process of affixing a ready made tie to the neck it has been generally necessary to secure it by passing a band, or to join two sections 35 or portions of a band, which is secured at one end to the tie, around the collar band. In some cases means have been provided to guard against rotary movement of the tie by employing tabs projecting oppositely from the knot to limit accidental movement, and in other cases an element carrying a slot adapted to straddle the shank of a collar button has been employed to supplement the band holding means. However, the band holding means makes it very difficult to 45 conveniently employ these ties with a starched, turned-down collar.

My present invention aims to provide a necktie which will be free from the inherent inconveniences and annoyances of the above referred to class, and which, in addition, has a distinct advantage over the class wherein the tie is tied by the user himself. By eliminating that feature which has made it heretofore advisable to use a neckband portion of the tie surrounding 55 the neck, I have designed ways and means to

provide the maximum of neck comfort by removing all pressure around the neck caused by the neckband. This invention provides a necktie which has no portion to surround the neck and which may be positively fixed on a collar 60 button and which will maintain the desired position to the collar. Among the advantages, aside from obvious ones of coolness, comfort etc., is the fact that the tie may be secured very tightly in its place without disarranging the 65 collar assembly, exerting pressure on the neck, impairing the wearing qualities or appearance of the tie, and the fact that it may be positioned easily, conveniently and positively to a collar button.

Typical constructions in my invention are illustrated in the accompanying drawings in which:

Figure 1 is a side elevation with parts broken away of my invention in a collar assembly.

Figure 2 is a side view illustrating details of the above.

Figure 3 is a side view of parts of Figures 1 and 2 in detail.

Figure 4 is a side view of parts complementary 80 to the invention.

Figure 5 is a rear view in perspective of a preferred form of a part of one form of the invention.

Figure 6 is a rear view in perspective illustrating the invention in a typical form.

Figure 7 is a side view in section of Figure 6.

Figure 8 is a side view of a modified form.

Figure 9 is a side view on section of a modification of a detail of the invention.

Figure 10 is a side view of a modification of a part complementary to the invention.

Figure 11 is a view in section of a modified adaptation of the invention.

The essential features of this invention lie, 95 among other things, in the co-operable action and relation between a form element which carries the necktie and a collar button. The collar button is adapted to cooperate with the form element, and the form element is adapted to cooperate with the collar button by means of the provision for a stud and socket arrangement between the two; either may carry the socket or either may carry a form of stud, or both a stud and socket may be carried by either or both. Certain preferred form of construction and modified forms of such will now be described and in which, it will be observed, adequate provision is made for properly adjusting and positioning the tie by means of a novel arrange- 110

ment whereby the tie is rotatably adjustable and longitudinally adjustable while at the same time being firmly but detachedly secured to the collar button.

5 Referring to the drawings: In Figure 1 I illustrate, with parts broken away, a conventional collar and necktie assembly in which 1 indicates the outer fold of a turned-over collar, 1a the inner fold around which a necktie band is 10 eliminated, and 1b illustrates an end of 1a. The conventional four-in-hand tie x has a knot 2 and a pair of streamer ends 3 and 3a. The rear end 2a of the knot 2 is adjacently confronting the button-holed tab ends of 1a. In this figure my 15 improved necktie is in position and has the same general appearance minus the neckband surrounding the neck as any other tie of the four-in-hand class. In dispensing with the band portion around the neck there is a saving in material and an increase in physical comfort. The tie x is held in proper position by the collar button as shown in detail in Figure 2 in which a 20 form element 4 is shown covered by the knot 2. In Figures 2 and 3 my invention is illustrated in 25 a preferred form: The form element 4 has at the rear an annular recess 5 having a side wall 6 substantially cylindrical in shape and an end wall concave in shape as illustrated. Projecting outwardly from the annular recess 5 is a 30 stud 7, preferably threaded, circumferentially spaced from the wall 6 of the annular recess 5. As shown in Figure 2 this stud 7 is received in a socket 8c (Figure 4) extending in the shank of the collar button 8. This socket is preferably 35 internally threaded to engage the external threads on the stud 7. The forward side of the rear end of the collar button rests against the inner side of the neckband 1e of the shirt and the shank passes through button holes provided in 40 the neckband portions 1e and 1d and the collar 45 band portions 1c and 1b and the rear wall of the enlarged forward stud end of the collar button confronts the collar as is customary. On the forward end the collar button stud is preferably convex in shape 8b, and immediately behind the convex end the wall is preferably cylindrical 8a. As the stud 7 of the form element 4 is inserted in the socket 8c of the collar button and is screwed therein, the stud end of the collar button is drawn into the annular recess 5 and seated therein, the walls 8a and 8b resting 50 against the walls 6 and the concave end wall of 5. It will be noted here that the cooperable 55 action of the stud 7 and the socket 8c, and the cooperable action of the annular recess 5 (or socket) and the stud end portions 8b and 8a of the collar button are typical illustrations of the "stud and socket arrangement" hereinbefore and hereinafter referred to. In the foregoing illustrations referred to both the collar button and the form element 4 combine both stud and socket features. This form of the invention has 60 certain advantages because when the wearer begins to fasten his tie to the button the projecting stud 7 can easily be guided into the socket opening of the collar button, and the forward stud end of the collar button is received, or substantially received, in the annular recess 5 of the form element or in its equivalent an aligning recess in the tie material or thickness 2a in order that the material on the form element 65 may press against or closely confront the tab of the collar, thereby hiding the fixing means 70 as well as providing frictional engagement of 75 the tie with the tab to assist in maintaining

position and appearance, as well as providing compensating means for variation in thickness, of collar or tie or both. If the threads be of rapid pitch several turns of the tie knot will draw the collar button stud into the annular recess 5 and provide a firm engagement. By placing a finger between the neck and the rear end of the collar button, the button may be prevented from turning, then, by continued tightening, the rear end of the collar button will be drawn tightly against the neckband while the rear end 2a of the tie knot will be pressed against the collar band. When sufficiently tightened a partial twist of the tie knot will rotate both button and tie sufficiently to position the tie. Thus, it will be seen that the tie may be both rotatably adjusted and longitudinally adjusted on the collar button by a simple operation while it is being detachably held thereon and, it will also be seen, that my novel construction accomplishes this even with a collar button having a forward stud or flange end, which is the preferable collar button construction because it permits of fixing the collar tabs and/or shirt tabs one by one and holding same 100 securely in place before my improved tie or any other tie is positioned. Tightening the tie puts no pressure on the neck, nor does the button press the neck. The form element 4 is sufficiently covered by necktie material 2 and 2a to 105 be completely hidden from view save for the annular recess 5. The annular recess 5, it should be pointed out, while shown in the drawings as a stud receiving recess provided in the form element, may be of shallow depth, and, in fact, 110 may not be provided in the form element at all, but in or by the material 2a of the tie, and this is within the spirit of the invention as illustrated in Figure 2 wherein the material 2a of the tie-knot 2 is clearly shown positioned 115 behind the front face of the forward stud or flange on the collar button, and, it is obvious, the above referred to recess may be governed as to depth and/or area wholly or partially by the thickness and/or contour of this material 2a. 120

Figures 6 and 7 illustrate the application of the principle to a bow tie x' in which the form element 4a is of contour adapted to conform to proper shape for this class of tie 3c and 3d illustrate the conventional ends of the bow and 125 2c illustrates the holding knot.

In Figures 8 and 9, the collar button and form element are shown provided with double stud and double socket characteristics respectively. The collar button, Figure 8, has the socket opening of Figure 4 replaced by the projecting stud 7a, and the form element Figure 9, has, in addition to the annular recess 5, an inwardly projecting socket 8d. In these forms also, the stud 7a and the socket 8d are preferably threaded.

In Figures 10 and 11 further modifications of this principle are illustrated: Figure 10 shows the collar button having its forward stud end threaded, as at 8a' to be received in the annular recess or opening 5' by the internally threaded wall 6' of the form element 4c which is in the form of an elongated band having an inner wall 9 through which a necktie 3 is passed and which may be tied by the wearer after the 140 form element 4c has been engaged with the collar button.

From the foregoing it will be seen that from the principle of this invention a variety of forms thereof may be constructed too numerous 145

to illustrate and describe as for instance a combination of threads and friction grip, or variations and modifications of combinations, the essence of which has now been disclosed.

5 Figure 5 illustrates a typical form element 4 for a tie of the four-in-hand type. The necktie is suitably fastened over the form and conceals the form. When complete providing, of course, a ready made tie. It is to be understood 10 of course, that the form element may be of any suitable shape or size, or any suitable material.

A fundamental feature of this invention is included in the term "stud and socket arrangement" and in order that it will be better understood I shall point out that typical illustrations of "stud" coming within its meaning are: the element 7, the element portions 8a and 8b, the element 7a, the element portions 8a' and 8b, or a combination of the above; also, 15 I shall point out that typical illustrations of "socket" coming within its meaning are: the recesses or openings 5, 8c, 8d and 5' either singly or in combination; and, also, do I wish to point out that on either of the elements, or on 20 both, I may employ various modifications and combinations of either stud or socket or both. The invention is susceptible to various changes in detail and construction without departing from the spirit and scope as illustrated, described and claimed.

I claim:

1. In combination, a necktie, a form element to hold the necktie and including a cooperable member of a cooperable stud and socket arrangement, said cooperable member adapted to engage a collar button having a shank, and combined detachedly holding, rotatably adjusting, longitudinally adjusting and inwardly rotatable tightening means included in said cooperable member for detachedly holding said form element on, for rotatably and longitudinally adjusting said form element on, and for inwardly rotatably tightening said form element to, a collar button for the purpose of providing 45 secure holding means for a necktie.

2. In combination, a necktie having a knot formed therein and including a form element including at least one engageable member of a stud and socket arrangement, a collar button having a shank and including at least one engageable member of a stud and socket arrangement, said form element engageable member adapted to engage said collar button, and combined detachedly holding, rotatably adjusting, 50 longitudinally adjusting and inwardly rotatable tightening means included in said form element for co-acting with said collar button engageable member for detachedly holding said necktie on, for rotatably, and longitudinally adjusting said necktie on, and for inwardly rotatably tightening said necktie to, said collar button for the purpose of providing secure holding means for a necktie.

3. In combination, a necktie having a knot formed therein and including a form element including at least one engageable member of a stud and socket arrangement, a collar button having a shank and including at least one engageable member of a stud and socket arrangement to cooperably engage the engageable member of the form element, combined detachedly holding, rotatably adjusting, longitudinally adjusting and inwardly rotatable tightening means included in said engageable members to co-act 75 for detachedly holding said necktie on, for ro-

tatably and longitudinally adjusting said necktie on, and for inwardly rotatably tightening said necktie to, said collar button, and means included in the necktie whereby the material of the tie at the rear of the knot may be forced against the tab of a collar, for the purpose of providing secure holding means for a necktie. 80

4. In combination, a necktie having a knot formed therein and including a form element including at least one engageable member of a stud and socket arrangement, a collar button having a shank, a rear head and a forward head including at least one engageable member of a stud and socket arrangement, said form element engageable member adapted to engage said collar button, and combined detachedly holding, rotatably adjusting, longitudinally adjusting and inwardly rotatable tightening means included in said form element for co-acting with said collar button engageable member for detachedly holding said necktie on, for rotatably and longitudinally adjusting said necktie on, and for inwardly rotatably tightening said necktie to, said collar button for the purpose of providing 90 secure holding means for a necktie. 95

5. In combination, a necktie having a knot formed therein and including a form element, a collar button having a shank spacing a forward head and a rear head, an annular recess provided in the forward head and extending into the shank, a stud carried by the form element to engage the annular recess in the collar button to provide a cooperable stud and socket arrangement including combined detachedly holding, rotatably adjusting, longitudinally adjusting and inwardly rotatable tightening means included in said form element for co-acting with said collar button annular recess for detachedly holding said necktie on, for rotatably and longitudinally adjusting said necktie on, and for 105 inwardly rotatably tightening said necktie to, said collar button.

6. In combination, a necktie having a knot formed therein and including a form element, a collar button having a shank spacing a forward head and a rear head to hold the tabs of a collar, an annular internally threaded socket leading from the forward head into the shank, an externally threaded stud carried by the form element to engage the socket in the collar button to provide a cooperable stud and socket arrangement including combined detachedly holding, rotatably adjusting, longitudinally adjusting and inwardly rotatable tightening means included in said form element for co-acting with 110 said collar button annular socket for detachedly holding said necktie on, for rotatably and longitudinally adjusting said necktie on, and for inwardly rotatably tightening said necktie to, said collar button, and means included at the rear 115 of the tie-knot to receive the face of the forward head of the collar button, and arrangement of tie-material at the rear of the knot whereby said material may be forced against the tab of a collar by tightening said threaded stud in 120 said threaded socket.

7. In combination, a form element for a necktie having a recess necktie material substantially covering the collar tab-confronting face of said form element and surrounding said annular recess at the rear of the form element, a collar button having a forward head, a shank and a rear head, an internally threaded socket provided in said collar button, and a threaded stud projecting rearwards from said form element 125 130 135 140 145 150

and substantially centrally of said annular recess whereby rotary movement of said form element detachedly engages said socket and may force the material of the rear face of said form element against the collar tab and cause said annular recess to surround the forward face of the forward head of said collar button.

8. In a combination as claimed in claim 7, necktie material forming a necktie and surrounding the form element, and an annular opening in the material at the rear of the knot and aligning with the annular recess provided in the form element. 80
